CLAIM

(21) Appl. No.: **29/163,731**

The ornamental design for a software application interface window for a display screen of a computer, as shown and described.

(22) Filed: **Jul. 10, 2002**

DESCRIPTION

(51) LOC (7) Cl. **14-02**

The single FIGURE is a front view of a software application interface window for a display screen of a computer showing the new, original, and ornamental design. The broken line drawing of a display screen is for illustrative purposes only and forms no part of the claimed design.
